UNITED STATES PATENT OFFICE.

FRANK CORDES, OF OAKMONT, PENNSYLVANIA, ASSIGNOR TO UNITED ENGINEERING AND FOUNDRY CO., OF PITTSBURGH, PENNSYLVANIA, A CORPORATION OF PENNSYLVANIA.

ANNEALING-BOX.

1,047,390.

Specification of Letters Patent. Patented Dec. 17, 1912.

Application filed March 4, 1912. Serial No. 681,499.

To all whom it may concern:

Be it known that I, FRANK CORDES, a citizen of the United States, and resident of Oakmont, in the county of Allegheny and 5 State of Pennsylvania, have invented a new and useful Improvement in Annealing Boxes; and I do hereby declare the following to be a full, clear, and exact description thereof.

10 My invention relates to annealing boxes and more particularly to that type formed by casting, the sides, ends and top integral with each other.

The object of my invention is to 15 strengthen and stiffen such type of annealing box in such a way as to prevent the bulging or buckling which has been one of the most serious difficulties encountered in the use of these cast-metal boxes.

20 To these ends my invention comprises the novel features hereinafter set forth and claimed.

In the drawing Figure 1 is a side view 25 partly broken away of my improved box; Fig. 2 is a bottom view partly in section on the line 2—2 Fig. 1; and Fig. 3 is an end view.

The top 2, sides 3 and ends 4 of my improved box are cast integral with each other, 30 and the hollow ribs 5 extend up the sides of the box and over the top thereof. Extending longitudinally of the box, around the sides and ends are the ribs 6 and 7, said ribs uniting with the transverse ribs 5 where 35 they intersect. The diagonal or converging ribs 8 are arranged between the transverse ribs 5 along the sides as indicated in Fig. 1, said ribs uniting with the longitudinal ribs 6 and 7 and rising preferably at the lower 40 ends of the transverse ribs 5. These con-

verging ribs unite at their apex with the upper longitudinal rib 6. In this manner I provide a very strong rigid construction as the converging ribs form with the longitudinal rib 7 A-shaped braces in the walls 45 of the box. These diagonal ribs 8 are preferably extended to form an inverted Y by the vertical portion 9 which strengthens the upper portion of the box. At the ends of the box the diagonal ribs 10 unite with the 50 longitudinal ribs 6 and 7 and the vertical portion 11 likewise forms a Y as in Fig. 1.

By the employment of the diagonal ribs uniting with the longitudinal ribs in the manner described I brace and strengthen 55 the side walls of the box, so that the bulging or buckling of the box is prevented and its life greatly increased.

What I claim is:

1. An annealing box formed of an integral casting, having a plurality of external longitudinally extending horizontal ribs intermediate the top and bottom of said box, and converging ribs rising from the bottom of the box and meeting the upper of said 60 longitudinal ribs at their apex.

2. An annealing box formed of an integral casting having a plurality of external transverse ribs, a plurality of external longitudinally extending horizontal ribs meeting 70 said transverse ribs, and converging ribs rising from the lower ends of said transverse ribs and meeting the upper of said longitudinal ribs at their apex.

In testimony whereof, I the said FRANK 75 CORDES have hereunto set my hand.

FRANK CORDES.
